United States Patent Office

Des. 177,611
Patented May 8, 1956

177,611

SPOON OR SIMILAR ARTICLE

William T. Brown, Attleboro, and Joaquin Prado, Taunton, Mass., assignors to R. Wallace & Sons Manufacturing Company, Wallingford, Conn., a corporation of Connecticut

Application August 19, 1955, Serial No. 37,579

Term of patent 14 years

(Cl. D54—12)

FIG. 1

FIG. 2

FIG. 3

41 14

51 15

61 16

FIG. 7

FIG. 4

FIG. 5

FIG. 6

Fig. 1 is a front view, in elevation, of a spoon showing our new design;

Fig. 2 is a side elevational view thereof;

Fig. 3 is a rear elevational view thereof;

Figs. 4, 5 and 6 are sectional views on the lines 4—4, 5—5 and 6—6, respectively, of Fig. 1; and

Fig. 7 is a front elevational view, on a larger scale, of the handle.

We claim:

The ornamental design for a spoon or similar article, substantially as shown.
